US0D1071100S

(12) **United States Design Patent** (10) **Patent No.:** **US D1,071,100 S**
(45) **Date of Patent:** **** Apr. 15, 2025**

(54) **HOSE CONNECTOR**

(71) Applicant: **TOYOX CO., LTD.**, Toyama (JP)
(72) Inventor: **Akihiro Inagaki**, Toyama-ken (JP)
(73) Assignee: **TOYOX CO., LTD.**, Toyama (JP)

(**) Term: **15 Years**

(21) Appl. No.: **29/851,444**

(22) Filed: **Aug. 29, 2022**

(30) **Foreign Application Priority Data**

Mar. 14, 2022 (JP) ..... 2022-005180 D

(51) **LOC (15) Cl.** 23-01
(52) **U.S. Cl.** **D23/266**

(57) **CLAIM**

The ornamental design for a hose connector as shown and described.

DESCRIPTION

FIG. 1 is a front view of a hose connector, in accordance with the design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a first perspective view of the rear, top, and left side thereof; and,

FIG. 8 is a second perspective view of the front, top, and right side thereof.

The shading on the entire surface of each figure is for specifying the shape of the three-dimensional surface of the hose connector.

1 Claim, 4 Drawing Sheets
